UNITED STATES PATENT OFFICE.

CLARENCE E. HOLLIDAY, OF DUNCAN, NEBRASKA.

CURRENT DISTRIBUTER AND TIMER.

1,268,716.

Specification of Letters Patent. Patented June 4, 1918.

Application filed January 4, 1916. Serial No. 70,277.

To all whom it may concern:

Be it known that I, CLARENCE E. HOLLIDAY, a citizen of the United States, residing at Duncan, in the county of Platte and State of Nebraska, have invented certain new and useful Improvements in Current Distributors and Timers, of which the following is a specification.

This invention relates, generally, to improvements in explosive gas engines; and the present invention has reference, more particularly to an electrical appliance or apparatus in the form of a timer for intermittently making and breaking the electrical circuits and to preferably connecting the sparking terminals or devices of a number of engine cylinders with the source or generator of the electricity, so as to successively ignite or fire the charges of the explosive medium in the explosion cylinders of a multicylinder engine.

My invention has for its principal object to provide a novel device of the above nature designed to supplant and supersede the ordinary vibrators that are now generally used conjunctively with the induction coils, to the end that the making and breaking of the electrical circuit may be controlled at a single point and the efficiency of the engine, as a whole, thus materially added to.

A further object of my invention is to provide a device of the type in question that is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form in the accompanying drawings, described in the following specification and then more specifically pointed out in the appended claim.

In the accompanying drawings wherein like characters designate like parts throughout the several views;

Figure 1 is a diagrammatic view illustrating my invention connected in circuit with a four cylinder engine of conventional form and a series of induction coils such as are generally employed in connection with engines of this type.

Fig. 2 is a view in side elevation of the timer shell or casing, showing the same embodying the principles of my invention.

Fig. 3 is a view in cross section of the timer's shell or casing, showing more clearly the relative position of my invention in conjunction therewith.

Fig. 4 is a similar view of the timer's shell or casing taken on line 4—4 of Fig. 2.

Fig. 5 is a longitudinal sectional view of the timer's shell or casing taken on line 5—5 of Fig. 4 in the direction indicated by the arrow head.

Referring now to the several figures of the drawings, the reference characters 1, 2, 3 and 4 indicate in this case, the four cylinders of an internal combustion engine, 5 designating a suitable frame upon which they are mounted and the numeral 6 denoting the crank casing that is associated therewith.

The reference characters 7, 8, 9 and 10 indicate a series of induction coils, of a conventional type, either of the single or multi-coil form, the reference characters 11, 12, 13 and 14 indicating the binding posts of the secondary windings of the coil, the said windings thereof being in circuit with the sparking plugs 15 of the engine by means of wires 16, 17, 18 and 19.

The contact making and breaking device or timer, consists essentially of a suitable casing comprising a preferably cylindrical body portion or shell formed with an end wire 21 which is made with a socketed portion 23. Upon reference to Fig. 2, it will be noted that the width of the casing 20 is approximately twice the width of an ordinary timer shell or casing whereby it may readily accommodate the improved making and breaking device such as will be subsequently described. At suitable points about the periphery of the casing 20, I may provide lugs 24 which, being in turn provided with openings 25 may be utilized for the purpose of attaching the device to a suitable support.

Arranged within the casing 20 is a ring shaped member, as 26 which is made of a suitable material or composition of matter, such as fiber, hard rubber or the like, which is a non-conductor of electricity, the said member or element being suitably secured in place by means of screws 27 which are passed through holes in the casing 20 and through the element or member 26, the said

screws having their screw threaded end portions receiving suitable binding nuts 28, substantially in the manner shown in Fig. 3 of the drawings. These screws 27 may be insulated from the casing 20 as at 29 whereby they may be utilized to conduct a current independently of the said casing. At their inner ends, the screws 27 connect with the contact blocks or plates 30 that are counter-sunk in the member 26 substantially in the manner shown in Fig. 3. As usual, the inner faces of the contact blocks 30 are concaved as at 31, thereby conforming with the circular contour of the inner periphery of the member 26.

As clearly shown in Fig. 1, the contact blocks or plates 30 are inserted with other binding posts 32 of the conduction coils through the instrumentality of the conductors 33, one end of the said conductors being connected with the binding post 32 while their other ends connect with the screws 27 of the timer casing. Still another conductor 34 connects with other binding posts 35 of the induction coils and a post 36 of a source of power on the crank casing 6, as clearly shown in Fig. 1.

A hollow spindle 37 is now arranged in the casing 20 which is to be keyed to a suitable guide shaft (not shown) whereby it may be driven at a speed approximately half the speed of rotation of the crank shaft of the engine. The spindle 37 is provided at a certain point about its periphery with spaced bearing lugs 38 which being connected through the instrumentality of a pintle 39 may be utilized to pivotally support a timer arm of suitable configuration, such as designated by the numeral 40. At one end 40 the timer arm is branched as at 41 whereby it may be made to revolvably support a contact roller 42 as at 43 while its other end is connected with one end of a spring or other tensioning member 44 in the manner shown. 45 The spindle 37 is further provided with a lug 45 that is preferably arranged to project diametrically opposite to the lugs 38 above referred to and to which the other end of the spring 44 may be connected as shown in Fig. 3. Consequently it will be noted that the contact roller 42 will be held against the inner periphery of the member 26 at all times whereby during the rotation of the spindle 37 it will be brought into intermittent contact with the several contact blocks 30.

In order to complete the circuit through the contact blocks, which is of course, essential to the operation of the device, I may 60 connect the spindle 37 with the ground of the engine casing, through the instrumentality of a conductor 46, such as clearly shown in Fig. 1.

At a suitable point upon the inner periphery of the casing 20 I mount a carrying

plate 47 which, having a section of insulating material 48 interposed between the same and the inner periphery of the casing, may be secured thereto through the instrumentality of a screw as 49. The screw 49 may be passed through the insulating material and the casing, such as clearly shown in Fig. 4 carrying another section of insulating material 50 exteriorly of the casing, and being formed to receive a binding nut 51 whereby an electrical conductor may be secured thereto in the usual manner. The plate 47 is in turn hingedly connected to a contact arm 52 as at 53 the latter being normally held under tension of a coil spring or other resilient element 54 which connects with the arm and the plate, while at its free end is provided with a spring contact member 55 as at 56. Adjacent the arm 52 I mount a second plate 56 which is also insulated with respect to the casing 20 as at 57 and secured in place through the medium of a screw 58 similar to the screw 49 above referred to. Exteriorly of the casing 20 the screw 58 is provided with a section of insulating material as at 59 while it is also formed to receive a binding nut 60 of the usual construction.

The plate 56' is suitably bent as at 61 to form a carrying extension, the latter in turn supporting an adjustable contact point 62 as at 63. The coil spring 54 above referred to normally retains the arm 52 in a position whereby the contact spring 55 thereof bears against the point 52 of the plate 56' thereby providing for the passing of a current between the respective plates, as is obvious.

The screw 49 may now be connected in circuit with other binding posts 64 of the induction coils through the medium of the conductor 65 while the other screw 58 may be connected in circuit with other binding posts 66 of the induction coils through the medium of a conductor 67. Consequently when the arm 52 is in a position shown in Fig. 4, a circuit will be closed between the conductors 65 and 67 respectively and the several induction coils, thereby providing for the making and breaking of the circuit through the spark plug 15 of the engine cylinder.

With a view of properly operating the contact arm 52 at the desired moment in order to accomplish the making and breaking of the circuit through the several induction coils, I provide the hollow spindle 37, above referred to with an enlarged head 68 as clearly shown in Fig. 4. The head 68 is provided about its periphery with a series of depressions 69 which in turn form a series of spaced cam members as 70. I now provide the contact arm 52 with a carrying shaft 71 which is to be passed through an insulated portion 72 thereof, one end of the shaft carrying a contact roller 73 to engage with the periphery of the head 68, while its

other end receives a fastening nut 74 by which it may be held in a secure position. It is further pointed out that the carrying shaft 71 may be provided with sheets of insulating material as 75 to bear against each side of the contact arm, substantially in the manner shown in Fig. 4. When the roller 73 seats in one of the depressions 69 of the head 68 the contact arm will be in a position whereby the spring 55 thereof will bear against the point 62 of the other plate 56. However, when in engagement with either of the hands 70, the contact arm will be held out of engagement with the point 62 as above mentioned.

The operation of my invention is substantially as follows:—The crank shaft of the engine being turned in the usual manner, prior to the starting of the engine, the hollow spindle 37 will be rotated, as before stated, thereby causing the contact wheel 42 to move about the inner periphery of the element 26 and thereby have successive engagement with the several contact blocks. Consequently when the parts assume a position as shown in Fig. 1, the respective contact wheel 42 will engage with the adjacent contact block 30 at a point substantially midway the end of the latter whereas the other wheel 73 will enter one of the depressions 69 of the head 68 thereby allowing contact of the spring 55 of the contact arm 52 and the point 62. Immediately upon contact of the spring 55 and the point 62 the circuit will be closed through the several induction coils which will obviously cause the sparking of the respective spark plugs; this being the spark plugs 15 of the second cylinder of the engine when the parts are in the position shown in Fig. 1. However this closing of the circuit through the induction coils is only momentary and is immediately broken upon the sparking of the respective plugs. This closing of the circuit occurs simultaneously with the contact wheel 42 reaching a certain point on each of the contact blocks 30 thus providing for the sparking of the several plugs in proper sequence.

From the above it will be noted that the employment of the arm 52 and its associated mechanisms eliminate the use of the ordinary vibrators on the induction coils, which,

as a general rule get out of order very easily. By eliminating the vibrators on the induction coils and connecting the resultant points 55 with the screws 49 and 58 respectively, the desired result may be obtained.

This type of device is especially designed for use in connection with Ford automobiles although, as apparent, it may be advantageously used in connection with different types of engines and timers, should the occasion so require.

From the above it is believed that the advantages and novel features of my invention 65 may be readily understood and therefore further details in construction are deemed unnecessary.

In reducing my invention to practice I find that the form referred to herein as the 70 most practical and preferred embodiment is the most efficient, but realizing that certain conditions will necessarily vary in concurrence with the adoption of my device, I desire to emphasize the fact that various minor 75 changes in the details of construction and in the proportion of parts may be resorted to when required without sacrificing any of the advantages of my invention as defined in the appended claim.

Having thus fully described my invention, what I claim as new and desire to secure by Letters Patent is:

An ignition timer for internal combustion engines, comprising the usual shell, insulated contacts and rotary brush, a cam within the shell and connected with the brush to rotate therewith and having cam elements corresponding in number with the insulated contacts, opposed insulated elements mounted within the shell, a contact adjustable on one of the insulated elements, an arm hinged to the other insulated contact, a spring contact on the arm disposed to co-act with the adjustable contact, a spring pressing the 85 free end of the arm inward, and a roller adjustable on the said arm and co-acting with the said cam.

In testimony whereof I affix my signature in presence of two witnesses.

CLARENCE E. HOLLIDAY.
